UNITED STATES PATENT OFFICE

2,523,406

INSULATED ANODE FOR CATHODE-RAY TUBES

Marshall P. Wilder, Stamford, Conn., assignor to Remington Rand Inc., New York, N. Y., a corporation of Delaware

Application June 25, 1949, Serial No. 101,283

2 Claims. (Cl. 250—141)

1

This invention relates to cathode ray tubes, and has particular reference to the structural mounting of a high voltage anode for those tubes which have metallic envelopes.

The conventional design of cathode ray tubes includes an envelope of glass, an electron emitting device, generally called an electron gun, an enlarged volume into which the cathode ray is projected, and an end face plate which is coated with a film of luminescent material. Electrons, generated and projected by the electron gun, pass into the enlarged volume where they may be deflected to form a pattern and finally strike the luminescent material which is caused to fluoresce and show a visible picture.

The enlarged volume is often formed in a conical shape and the envelope material may be either of glass or metal. If it is made of glass, or other insulating material, the inside surface is covered with a non-reflecting conductive coating to which a positive potential of several kilovolts above cathode potential is applied. This conductive coating serves several purposes. It aids in accelerating the electron beam toward the screen; secondary electrons formed at the screen are absorbed; and light reflections from the screen are also absorbed.

The outside of the glass envelope is often covered with a conducting layer and grounded to help screen the tube from outside electrostatic fields and to form a capacitor to be used in a filter circuit.

If a metallic sleeve is used for all or part of the enlarged portion of the envelope, no inside conductive coating is necessary since the metal itself serves the purpose. In addition, the metal sleeve is opaque and can easily be made with a non-reflecting inside surface.

A metal sleeve having a positive potential of several kilovolts above ground creates many insulating problems especially when the tube is mounted inside a cabinet with associated circuit equipment in close proximity. Also the absence of the filter capacitor requires another high voltage component to be added to the equipment.

The present invention includes a new design for cathode ray tubes using a metallic sleeve as part of the tube envelope. A second conducting sleeve is mounted inside the first, having about the same shape but uniformly spaced therefrom and mounted on insulating spacers. The outer metal sleeve, which is sealed vacuum tight to the rest of the envelope material, is operated at ground potential. The inner metal sleeve is ex-

2

posed to vacuum on all sides and is connected to the source of positive potential.

One object of the invention is to provide a cathode ray tube of improved design which avoids one or more of the disadvantages and limitations of prior art arrangements.

Another object of this invention is to improve present day cathode ray tubes having metallic sleeves so that both the sleeve and the cathode may be operated at ground potential.

Another object of the invention is to provide a cathode ray tube having a predetermined built-in filter capacitor.

For a better understanding of the present invention, together with other and further objects thereof, reference is made to the following description taken in connection with the accompanying drawings.

Fig. 1 is a longitudinal cross section of a cathode ray tube according to the invention.

Fig. 2 is a cross sectional view of the tube of Fig. 1, taken along line 2—2 of that figure.

Referring now to Fig. 1, a glass neck 10 is employed to house the electron gun 11 which may be of conventional construction. At the screen end of the neck an enlarged or bell-shaped portion 12 is formed to act as the supporting base for a conductive coating 13. The rim of the enlarged portion 12 is sealed to a metallic sleeve 14 which is generally conical in shape. At the large end of the sleeve 14 a transparent glass plate 15 is mounted with its rim sealed to the edge of the sleeve. The inside surface of the glass plate 15 is coated with fluorescent material 16 as is usual in the construction of cathode ray tubes.

Inside the metallic sleeve and generally parallel to it is mounted a second metallic sleeve 17. To provide the proper spacing and electrical insulation, small ceramic insulators 18 are positioned between the two sleeves. The difference of potential between the two sleeves 14 and 17 may be as great as 40 kilovolts, but since the inner sleeve is surrounded by a vacuum, the distance between them need not be more than $\frac{3}{8}$ of an inch.

At the small end of the inner sleeve 17, three springs 20 are secured by welding or riveting. The springs extend beyond the rim of the sleeve 14 so that when the tube is completely assembled, the ends of the springs make contact with the conductive coating 13. A conductive lead-in wire 19 is mounted in the bell-shaped portion 12 to apply a high potential to coating 13 and sleeve 17.

At the large end of inner sleeve 17 a second set of springs 21 is mounted to make conductive con-

tact with the fluorescent coating 16. A small conductive terminal lug 25 is welded to the outside surface of sleeve 14 to facilitate the connection to ground and the negative terminal of a source of high potential.

The tube is assembled in the following manner: First, the inner sleeve 17 is placed in the outer sleeve 14 and secured by fastening the insulator blocks to each sleeve. Second, the face plate 15, without the fluorescent screen 16, is placed on the end flange of sleeve 14 and the metal-to-glass seal 23 is made. Third, the neck 10, without the electron gun, is sealed to the flange 22 at the small end of sleeve 14. At this point all the major components have been assembled in a single arrangement. Next, the fluorescent screen material 16 is added and the conductive coating 13 is painted on the inside of volume 12.

The tube is now ready for the final assembly operations. The entire arrangement is baked to remove all traces of moisture; then the electron gun 11 is mounted in the neck 10; the tube is exhausted, processed, and sealed.

The operation of the tube is the same as the usual form of cathode ray tube except that the outer sleeve 14 is grounded and the inner sleeve 17 is kept at a high potential by means of a battery 26 or other convenient source. Electrical connection for the inner sleeve is made by means of the lead-in terminal 19, springs 20 and conductive coating 13.

Since the double sleeve is to be used as a capacitor in a filter circuit, it is essential that the desired capacity be achieved within reasonable limits. This may be accomplished by carefully gauging the insulated spacers 18 and holding the area of the inner sleeve to close limits. In case a change of circuit constants demands a change of filter capacity, the new value may be easily obtained by using an altered set of spacers.

While there have been described and illustrated specific embodiments of the invention, it will be obvious that various changes and modifications may be made therein without departing from the field of the invention which should be limited only by the scope of the appended claims.

What is claimed is:

1. A cathode ray tube comprising, a tube envelope for enclosing and supporting an electron gun at one end and a fluorescent screen at the opposite end, an outer metallic sleeve forming

part of the envelope adjacent to the fluorescent screen, a connection between the outer sleeve and ground, an inner metallic sleeve mounted in parallel relationship to the outer sleeve, a connection between the inner sleeve and a source of high positive potential, a plurality of spring connectors secured to the inner sleeve and projecting longitudinally to make contact with the fluorescent screen, and fixed insulator supports between the inner and outer sleeves for securing the inner sleeve in position.

2. A cathode ray tube comprising, a tube envelope for enclosing and supporting an electron gun at one end and a fluorescent screen at the opposite end, a conductive coating mounted on the inside of said envelope adjacent the electron gun, a connection between the conductive coating and a source of high positive potential, an outer metallic sleeve forming part of the envelope adjacent to the fluorescent screen, a connection between the outer sleeve and ground, an inner metallic sleeve mounted in parallel relationship to the outer sleeve, a plurality of spring connectors secured to the inner sleeve and projecting longitudinally to make contact with the fluorescent screen, one or more spring connectors secured to the inner sleeve and projecting longitudinally to make contact with the conductive coating, and fixed insulator supports between the inner and outer sleeves for securing the inner sleeve in position.
